MORITZ L. MUELLER, OF SEATTLE, WASHINGTON, ASSIGNOR TO NORTHWEST BLOWER KILN COMPANY, OF PORTLAND, OREGON, A CORPORATION OF WASHINGTON.

METHOD OF CONTROLLING THE PROCESSING OF MATERIALS.

Application filed November 9, 1927. Serial No. 232,094.

This invention relates to a method of controlling the processing of materials subject to shrinkage or swelling during treatment, and it has for its object to control the treatment accorded such material in accordance with the degree of shrinkage or swelling. In many industrial processes materials being treated are subjected to variations of temperature, moisture, drying, etc., in such manner that the material is caused to shrink or swell. For example, when lumber is being dried shrinkage of the wood is in close relation to its moisture content changes, and thus the degree of shrinkage acts as a reliable index as to when the drying should be discontinued or changed.

According to the present invention, a method is provided whereby the shrinking or swelling of the material being treated operates to close an electric circuit for the purpose of energizing a signal or operating control mechanism by which the treatment of the material may be automatically changed. In the lumber seasoning processes in common use, the time of terminating or changing the drying processes is determined by weighing samples of the drying wood. This is inconvenient, because it requires a person to enter a hot drying chamber, and it is inefficient because considerable time elapses before the result of the weighing is obtainable. During this elapsed time harm may be done to the material being treated. The method of the present invention is useful in any process wherein shrinkage or swelling of the material is involved, and wherein there is a definite relation between the amount of shrinkage or swelling and the process.

In the accompanying drawing, I have diagrammatically illustrated one form of apparatus which may be utilized in practicing the method of the present invention. However, it is to be understood that the illustration of this apparatus is merely for purposes of explaining the method, since it is clear that the method may be carried out in many different ways.

In the drawing:

Fig. 1 is a plan view,

Fig. 2 is a side view, and

Fig. 3 an end view of an apparatus adapted for use in the practice of the method.

Fig. 4 is a diagrammatic view, illustrating a plurality of the mechanisms of Figure 1,

connected in series for a purpose which will be hereinafter described.

Like numerals designate corresponding parts in all of the figures of the drawing.

In the drawing 1 designates a base plate which may be provided with a cover (not shown). A bell crank lever comprising a short arm 2, and a long arm 2^a is pivoted at 3 upon the base, and carries a prong 4 which projects downwardly from the outer end of the short arm 2 of the lever. The extremity 60 of the long arm 2^a of the lever carries an electrical contact point 5, which co-acts with an electrical contact point 6, that is supported by means of a spring tongue 7 from a swinging lever 8, said lever being pivoted at 8^a to the base 1. The outer portion of the lever 8 moves through a slot 9 formed in the end wall of the casing constituting the base, said end wall being graduated as indicated at 10. The contact point 5 is connected by a conductor 11, with one side of an element 12, and the other side of this element 12 is connected by conductor 13, with a battery 14. The other side of the battery is connected by a conductor 15 with the contact point 6. Thus, it 75 will be seen that whenever the contact points 5 and 6 touch each other a circuit will be completed to energize element 12. This element may be either a visual signal, such as an electric light, an audible signal, such as a bell, or a controlling device, such as in one of the well known electrically operated valves purchasable upon the open market, and which may control steam, compressed air, water or any other liquid or gas used in the treatment 85 of the material being processed.

A piece of the material being treated is indicated at 16, and when the invention is to be practiced the structure illustrated is placed upon the material 16, the prong 4 being engaged with said material along with fixed prongs 17 of the base. The prongs 17 hold the casing or base in fixed position with relation to the material 16. The arrangement illustrated is one adapted to control the 100 process under the influence of shrinkage. If the process is to be controlled under the influence of swelling, it would only be necessary to put the contact 6 upon the opposite side of the arm 2^a. As the material shrinks the pin 4 is moved toward the left in Figures 1 and 2 to swing the long arm of the bell crank lever toward and to bring contact point 105

5 into engagement with contact point 6, thereby completing the circuit as aforesaid.

In order to avoid any binding, due to the movement of the pin 4, upon an arc, said pin 5 may be made of such flexibility as to be slightly yieldable laterally. By mounting the contact pin 6 on a movable and definitely settable lever 7, I am able to provide for a variety 10 of materials which will shrink different amounts, or to provide for different amounts of shrinkage in the same material. The graduated scale 10 permits the setting of the lever 8, repeatedly at a selected point.

In carrying out the invention the degree of 15 shrinkage of any given material between its original or green condition, and the final condition at which the treatment is to be discontinued or changed, is determined. The lever arm 8 is then placed in such position, with 20 respect to the scale, that its contact 6 will be touched by the contact 5, when the prong 4 has moved such determined distance. The reading of the scale 13 is noted at the time 25 the treatment is started. The material is then treated or dried until the electric circuit is completed by the contact of points 5 and 6, at which time treatment is discontinued. Repeated using of the scale may be 30 made upon the same material without further experimentation, by a corresponding setting of the lever 8 at the beginning of each operation.

In Figure 4 I have illustrated three of the 35 circuit closing devices of Figures 1 and 2, connected in series and mounted upon three separate pieces of material to be treated. This arrangement forms several gaps in the electric circuit and automatically selects the slowest sample of material to shrink or swell 40 to the predetermined point, it being apparent that the whole circuit is completed only when all three of the gaps are closed. Or several scales setting on a single piece of material, each set for a different amount of shrinkage 45 or swelling will show progressively when these conditions have been created.

Having described my invention, what I claim is:

1. The herein described method of controlling 50 the processing of material subject to shrinkage or swelling in its treatment, which consists of applying to said material, while

under treatment an element operable under the influence of the variations in dimensions of the material, and varying the treatment 55 accorded to said material in accordance with the movement of said element.

2. The herein described method of controlling the processing of material, which is subject to shrinkage or swelling in its treatment, 60 which includes applying to said material an element operable under the change in dimensions of the material while being treated, and indicating by the movement of said element the time and nature of the steps to be taken 65 in the treatment thereof.

3. The herein described method of automatically controlling the processing of material subject to shrinkage or swelling in its treatment, which consists of applying to the 70 surface of said material an element operable under the influence of change of dimensions of said material, and utilizing the movement of said element to automatically operate a controlling device, by which the conditions 75 to which the material is subjected are changed.

4. The herein described method of controlling the drying of lumber, which consists of applying to said lumber an element operable 80 under the influence of change in dimension of said lumber under shrinkage, and varying the conditions to which the lumber is subjected in accordance with the movements of said element.

5. The herein described method of controlling the drying of lumber, which consists of applying to said lumber an element movable under change in dimension of said lumber under the influence of shrinkage and automatically controlling the conditions to which the lumber is subjected in accordance with the movements of said element.

6. The herein described method of controlling the drying of lumber in accordance with the rate of drying of the slowest drying of several pieces of lumber, which consists of applying to said several pieces elements arranged in series and automatically varying the conditions to which the lumber is subjected when the element of the slowest drying piece has been moved a predetermined degree.

In testimony whereof I affix my signature.

MORITZ L. MUELLER.
